UNITED STATES PATENT OFFICE.

NICOLAS POGOLSKI, OF WASHINGTON, DISTRICT OF COLUMBIA.

MEANS FOR PREVENTING THE DISASTROUS CONSEQUENCES OF THE ACCIDENTAL IGNITION OF THE GASOLENE OF AIRCRAFTS' TANKS.

1,300,190.

Specification of Letters Patent.

Patented Apr. 8, 1919.

Application filed June 13, 1918. Serial No. 240,563.

To all whom it may concern:

Be it known that I, NICOLAS POGOLSKI, of Washington, District of Columbia, have invented a new and useful Improvement in

5 means for Preventing the Disastrous Consequences of the Accidental Ignition of the Gasolene of Aircrafts' Tanks, which invention is fully set forth in the following specification.

10 My invention relates to new and useful means for preventing fires occurring in airplanes, and especially the firing of the gasolene supply, from becoming a source of danger to the operator and seriously destructive

15 in its effect upon the airplane, and the object of the invention is to provide such a means preferably under the control of the operator which by a most simple and natural action on his part will cause the quick release and dropping of the fuel tank and at the same time prevent leakage by reason of the rupture of the supply connection thereof.

20 The invention primarily consists in providing a support or false bottom for the gasolene tank, which support or false bottom is in turn supported upon releasing devices, which when withdrawn from their engaged position permit the tank and its support to drop free of the airplane.

25 The invention also consists in combining with the releasing devices a suitable power device for actuating the same, and a locking means under the control of the operator, whereby upon its actuation the release will be made through the action of the power device.

30 The invention also consists in providing means for rupturing the fuel supply connection of the tank that is operated through a connection between said means and the tank, whereby the weight and momentum of the tank in falling will supply the power for operating the rupturing means.

35 The invention also consists in providing means for continuing the flight for a short time after the dropping of the fuel tank.

40 The invention further consists in certain other features in the arrangement and construction of parts, all as hereinafter described and claimed.

In the accompanying drawings, illustrating the invention,

Figure 1 is a top or plan view;

Fig. 2 is a view in elevation;

Fig. 2^a of the drawing shows the connection between the tank of reserve and the motor.

My plan is as follows: I place the gasolene tank on a false bottom, A, B, C, D, (Fig. 1) which is held in its place by four bolts b, b, governed by the shafts N, N, each carrying two toothed wheels g, g. These wheels act on racks f, f, forming the prolongation of the bolts b, and withdraw the 60 bolts b, from their nests, n, n, thus leaving the false bottom free to fall down. The shafts N, N, are set in rotation by the shaft M, which is rotated by a powerful spring S, kept in the state of tension by the ratchet 65 wheel i. With raising of the stop t, by a pull given to the chain x (Fig. 3) the apparatus is set in action and the false bottom with the tank falls through. Further, by the same pull given to the chain a communication is automatically established between 70 the motor and a small gasoline tank of 75 reserve.

Fig. 2 represents the arrangement for the above purpose; p', is a pulley over which 80 passes a chain, or rope, x, one end of which is attached to the stop, t, and another end carries a ring, r'. Over another small pulley, p'', passes the chain, x', one end of which is joined to the chain x, at, f, and 85 another end passes under the pulley, z, then is fastened to it at, c; the pulley, z, is set on the protruding end of the valve, v. Through a pull given to the ring, r', the stop, t, is raised, at the same time the pulley, 90 z, is set in rotation; the valve, v, is turned and therewith the communication between the gasoline tank Q and the motor is established through the pipe, w.

Obviously the tube connecting the tank 95 with the motor must be severed from the latter that not a single drop of gasolene should be split on the plane. The apparatus F² and F³ is to answer this purpose.

The above connecting tube must be made 100 of soft metal, such as lead or red copper and is laid on a steel plate which passes

under a fixed roller that flattens the tube and drives out of it all gasoline; next the tube passes under a cutter that cuts through it.

- 5 In Fig. 2, *a*, represents a narrow steel plate which carries the tube *T* and is provided with four rollers *d*, *d*, rolling in the grooves of the two rails, *h*; *K* are the supports carrying the bearings of the rollers 10 *m*, which pass over the tube, flattens it, and drives out all the gasoline. Next, the flattened tube passes under the cutter *C*, which cuts through it and touches the strip *y*, of the red copper which is inlaid in the 15 middle of the plate *a*.

For setting in rolling the carriage carrying the plate, *a*, I purpose using the kinetic energy of the falling false bottom and do it in the following way: A chain (or rope), *l* 20 (Fig. 1 and Fig. 2) solidly attached to the false bottom at the point *p*, is led over the small roller, *O*, and wound on the pulley, *w*, which is provided with a hook, *e*; the chain, *l*, carries an eyelet at its end which eyelet 25 after the winding of the chain, *l*, around the pulley, *w*, is set on the hook, *e*. Thus by unwinding of the chain, *l*, the pulley, *w*, is set in rotation and the latter continues until the escape of the eyelet off the hook, *e*. 30 *s* is a spring to stop the plate *a* when the tube *T* is cut through. Farther on, on both ends of the pulley, *w*, there is a pulley, *v*, which pulleys are both connected by the ropes, *q*, with the plate, *a*. During the unwinding of the chain, *l*, the ropes, *q*, are wound on the pulley, *v*, and therewith the carriage with the plate, *a*, is drawn toward the false bottom, and it passes first under the roller, *m*, and then under the cutter, *c*. 35 40 With the installation of a small tank of reserve, the danger of the burning down of aeroplanes will be increased proportionately to the increase of the exposed surface. Therefore the small tank must be treated in 45 the same way as the large one in order to prevent its being the cause of the burning down of the aeroplanes.

The arrangement of Fig. 1 looks very bulky and heavy, but it is represented only 50 schematically; it will be the duty of the engineer to make it as light as possible. It is obvious that the length of the bolts, *b*, *b*, being, say, $1\frac{1}{4}$ inch a toothed wheel of, say, 55 3 inches diameter, to withdraw the bolts from their nests, must be turned by less than 60° , therefore only a small sector of the wheel would be necessary and the rest can be cut off. The same change could be made on the ratchet wheel.

60 It may be stated that in devising the above described invention the inventor has been guided by the following considerations that are of paramount importance. To release the tank, which with its fuel supply

weighs sometimes over half a ton, considerable effort would be required of the operator and could not be accomplished instantly as is desirable. The pilot of an aircraft in flames is often wounded, and besides his clothing is often set afire by a 70 jet of flaming gasoline. It is impossible therefore in such situations to require of the operator the heavy and slow task of releasing the tank, and for this reason it is considered absolutely necessary to impose upon 75 the operator only the slightest possible action on his part and to provide a power device in connection with the releasing means that can be set in action instantaneously by him without any appreciable effort. 80

What I claim is:—

1. Means for preventing the disastrous consequences of the ignition of the gasoline of air-craft tanks, comprising a false bottom held in place by a plurality of bolts 85 having each a rack portion, a power device, a power transmission device carrying pinions for operating said bolts through their racks, a ratchet locking means for said power device, whereby upon unlocking the 90 power device it is set in action to withdraw the said bolts.

2. Means for preventing the disastrous consequences of the ignition of the gasoline 95 of air-craft tanks, comprising a releasable fuel tank in combination with means for flattening and cutting the fuel pipe operable automatically through a connection with the fuel tank upon the descent of the latter. 100

3. Means for preventing the disastrous consequences of the ignition of the gasoline of aircraft tanks, comprising in combination, a releasable main fuel tank, an auxiliary reserve fuel tank, and means for automatically connecting the auxiliary tank with the motor when the main tank is released. 105

4. Means for preventing the disastrous consequences of the ignition of the gasoline of aircraft tanks, comprising a combination, a releasable fuel tank having a supply duct or pipe connected therewith, means for cutting and sealing said duct or pipe, said means being set in motion upon the movement of the tank relatively thereto. 115

5. A device of the character described comprising a releasable fuel tank having connection with a motor, in combination with means for cutting and sealing the connection between the fuel tank and the motor, said means including a shiftable element adapted to have a portion of the connection resting thereon, a sealing device arranged over said shiftable element, and a cutter device arranged over said shiftable element, said element being connected with the tank to be shifted by a movement thereof. 120

6. A device of the character described,

comprising a releasable fuel tank having a supply connection with a motor, in combination with means for cutting and sealing said connection when the tank is released, said 5 means including a flattening roller, a cutter element, and a shiftable member movable under said roller and cutter element and

carrying a portion of said supply connection, and a connection between said shiftable element and tank through which the former 10 is actuated.
